UNITED STATES PATENT OFFICE.

ADOLF GUND, OF NEW YORK, N. Y.

TOY ANIMAL.

Application filed January 25, 1921. Serial No. 439,781.

To all whom it may concern:

Be it known that I, ADOLF GUND, a citizen of the United States, and a resident of the city of New York, borough of the Bronx, 5 in the county of Bronx and State of New York, have invented a new and Improved Toy Animal, of which the following is a full, clear, and exact description.

The object of the invention is to provide 10 a new and improved toy animal arranged to afford considerable amusement to a child when playing with the toy animal.

Another object is to cause the toy animal to emit sounds on pressing and quickly releasing it while resting on a table, floor or other support, and to cause the toy animal to assume first a crouching position and then a forward jumping position.

Another object is to provide a toy animal 20 which is very simple and durable in construction and not liable to get easily out of order.

With these and other objects in view, the invention consists of certain novel features 25 of construction as hereinafter shown and described and then specifically pointed out in the claims.

A practical embodiment of the invention is represented in the accompanying drawings 30 forming a part of this specification, in which similar characters of reference indicate corresponding parts in all the views.

Figure 1 is a side elevation of the improved toy animal with parts shown in 35 section;

Figure 2 is a cross section of the same on the line 2—2 of Figure 1;

Figure 3 is a perspective view of the 40 spring device;

Figure 4 is an inverted plan view of part of the same; and

Figure 5 is a diagrammatic view of the 45 toy animal showing the successive positions it assumes on pressing and suddenly releasing it.

The toy animal illustrated in the drawings is arranged in the form of a dog, but it is expressly understood that I do not limit myself to this type of animal. The toy 50 animal shown comprises a body 10 having a head 11, a tail 12, fore legs 13 and hind legs 14, and the several parts are formed by a suitably constructed cover 15 of a textile material and a stuffing 16 of a loose, soft material such as cotton batting and the like. A spring device 17 is embedded in the stuffing

16 and comprises two flat springs 18 connected with each other by a top plate 29 which holds the springs 18 together in spaced relation. The forward ends of the springs 18 are provided with downwardly and forwardly extending members 19 extending into the fore legs 13 to stiffen the same and to allow the legs to bend, as hereinafter more fully explained. The lower ends 20 of the 60 leg members 19 are slightly curved forwardly and extend in close proximity to the bottoms of the fore legs 13. The rear ends of the springs 18 terminate in rear members 21 embedded in the stuffing of the hind legs 14 and each of the said rear members 21 has its upper portion 22 extending downwardly and rearwardly and having its lower portion 23 extending downwardly and forwardly. The lower ends 24 of the rear 70 members 21 are curved forwardly and extend in close proximity to the bottoms of the hind legs 14. By constructing the spring device 17 in the manner described and embedding it in the body 10 and the legs 13 and 80 14 of the toy animal, the latter can be readily pressed downward by the child into a crouching position, as shown in Figure 5, owing to the front and rear members 19 and 21 bending correspondingly. When the toy 85 animal is in this crouching position and is suddenly released by the child then the front and rear spring members 19 and 21 return to their normal positions and in doing so cause the toy animal to jump forward from the 90 crouching position into the forward erect position shown in Figure 5. The top plate 29 is preferably made of sheet metal with the bent sides under the springs 18 and with lugs 31 formed at the front and rear ends 95 of the plate and likewise bent under the springs 18 and onto the sides 30 to firmly embrace the springs 18 to hold the same in spaced parallel position.

A sounding device 40 is arranged within 100 the body 10 to emit sounds corresponding to those of the type of animal disclosed, and this sounding device 40 is provided with a bottom 41 resting on the top plate 29 of the spring device 17. The bottom 41 is connected by a bellows 42 with a top 43 and a spring 44 is interposed between the bottom 41 and the top 43 to hold the same normally spaced apart with the bellows 42 in extended position. On the top 43 is mounted the 105 usual sound producing means 45 in the form of a reed and tube. Now when the child 110

presses the body 10 downward the top 43 of the sounding device is pressed downward against the tension of the spring 44 whereby the air in the sound box is forced through 5 the sound-producing means 45 to sound the same. It is understood that this downward pressure also causes the spring device 17 and the animal to assume the crouching position previously mentioned. When the child re- 10 leases the pressure on the body 10 then the spring device returns to normal position and likewise the top 43, and in doing so air is drawn into the sound box to again be forced out on the next downward pressing of the 15 top 43, as above explained. In toy animals, such as a dog, for instance, the sounds are emitted on the downward movement of the top 43 of the sound box, but in animals like a cat, for instance, the sound device 45 is ar- 20 ranged to sound on the return or upward movement of the top 43 to produce a longer sounding action as that required for pro- ducing the "mew" sound in contrast to the quick, sharp bark of a dog.

25 Besides assuming crouching and forward jumping positions, as above described, the child may cause the toy animal to execute a somersault or similar trick performance on striking, for instance, a sharp blow with the 30 hand on the head of the animal.

From the foregoing it will be noticed that the toy animal shown and described is very simple and durable in construction and is not liable to get out of order easily.

35 Having thus described my invention, I claim as new and desire to secure by Letters Patent:—

1. A toy animal, comprising a body having flexible legs adapted to rest on a support, 40 a spring actuating device arranged within the said body and having resilient members extending in all of the said legs to normally stiffen the same, the said resilient members allowing the toy animal to assume 45 a crouching position on pressing the body downward and to cause the toy animal to jump forward on suddenly releasing the said body.

2. A toy animal, comprising a body having flexible legs adapted to rest on a support, 50 a spring actuating device arranged within the said body and having resilient members extending in all of the said legs to normally stiffen the same, the said resilient members 55 allowing the toy animal to assume a crouching position on pressing the body downward and to cause the toy animal to jump forward on suddenly releasing the said body, and a sounding device mounted on the said spring actuating device and having a spring- 60 pressed movable top member adapted to be actuated on pressing the said body.

3. A toy animal, comprising a stuffed body having fore and hind legs, and a spring device embedded in the stuffing of the said body 65 and having a pair of springs and a top plate connecting the springs with each other and holding the same in spaced relation, the springs having forwardly and downwardly extending front members arranged within the fore legs, and the springs having rear members extending within the said hind legs, each of the said rear members having an upper portion extending downwardly and rearwardly and having a lower portion 70 extending downwardly and forwardly.

4. A toy animal, comprising a stuffed body having fore and hind legs, and a spring device embedded in the stuffing of the said body and having a pair of springs and a top 80 plate connecting the springs with each other and holding the same in spaced relation, the springs having forwardly and downwardly extending front members arranged within the fore legs and the springs having rear 85 members extending within the said hind legs, each of the said rear members having an upper portion extending downwardly and rearwardly and having a lower portion 90 extending downwardly and forwardly, and a sound box resting on the said top plate and having a spring-pressed movable top member carrying a sound producing means, the said sound box being surrounded by the stuffing.

ADOLF GUND.
